(57) **CLAIM**

The ornamental design for a solar cell box, as shown and described.

DESCRIPTION

FIG. 1 is a first perspective view of a solar cell box showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the solar cell box thereof;

FIG. 10 is a perspective view of the using state of the solar cell box thereof; and,

FIG. 11 is an enlarged view of the selected portion in FIG. 2.

The broken lines shown in the drawings depict portions of the solar cell box in which the design is embodied that form no part of the claimed design.
